Patented May 14, 1918.

UNITED STATES PATENT OFFICE.

DANIEL YOUNG, OF BROOKLYN, NEW YORK, ASSIGNOR OF FIFTY-ONE ONE-HUNDREDTHS
TO HARRY E. MITTENTHAL AND AUBREY MITTENTHAL, BOTH OF NEW YORK, N. Y.

APPARATUS FOR TREATING AND FORMING WEIGHTED OR LOADED SHEET FABRICS.

1,266,373.

Specification of Letters Patent. Patented May 14, 1918.

Application filed July 17, 1917. Serial No. 180,987.

To all whom it may concern:

Be it known that I, DANIEL YOUNG, a citizen of the United States, residing in Brooklyn, in the county of Kings and State of New York, have invented certain new and useful Improvements in Apparatus for Treating and Forming Weighted or Loaded Sheet Fabrics, of which the following is a specification.

10 The objects of my invention or inventions herein disclosed are to provide a new and improved apparatus for treating sheet-fabrics, of any and all forms, in which in the course of such treatment the fabric-sheet is unrolled and rerolled, and in its passage from feed to receiving or take-up roll is supplied with any required impregnating, loading, weighting or surfacing material; the proper amount of such material supplied to the 15 fabric-sheet, of which, it is necessary to determine from time to time by weighing the same, until the required grade of the finished material has been reached by the deposition or impregnation of the fabric 20 with the required quantity of the impregnating or loading material; and may be applied to sheets of woven or knitted fabrics, leather, etc.; paper of all forms including sensitized photographic papers, etc.; but as 25 shown and described herein my said improved apparatus are those especially adapted for the water-proofing or, as it is commonly known in the art, "rubberizing" of woven sheet-fabrics.

30 My said improved apparatus is fully shown, described and claimed in the following specification, of which the accompanying drawing forms a part, wherein similar letters or numerals of reference 35 designate like or equivalent parts wherever found throughout the several views, and in which:

Figure 1 is a front end view in elevation of my improved combined weighing and 40 roll-shifting apparatus, for carrying my said method into effect, in position ready to be operated;

Fig. 2 is a side view of such apparatus looking toward the left of Fig. 1 in the direction of the arrow, in position upon the 45 front end of a rubberizing machine, only a small portion of which is shown; and

Fig. 3 is a front end view in detail partially in section and on an enlarged scale 50 from that shown in Fig. 1, of one of the

roll-supporting mechanisms showing the roll of fabric in position thereon.

Referring to the drawing:

The reference letter A, designates the front end of a fabric-sheet waterproofing 60 or "rubberizing" machine of an old and well known form, showing my improved combined roll-shifting and roll-weighing apparatus B attached thereto; C designates the steam-coil fabric-sheet supporting and drying bed; D the combined trolley-carriage and weighing scale of B; E the combined lifting and roll-swinging shift frame; and F, a roll of the sheet-fabric about to be treated, in position upon the supporting-shaft. 65

In the treating or rubberizing machine, the reference numeral 11 designates the knife-roll shaft, supporting and rotating the knife-roll 11', such shaft 11 being rotated to the right as shown by the arrow by the pulley 12, connected with a driving-pulley 13 by a belt 12'. Such knife-roll 11' is so called for the reason that just above it is located a spreading-knife, which extends 70 longitudinally thereof with just space enough between it and the peripheral surface of the roll, to permit the passage of the fabric-sheet H (shown in dotted lines) and the required quantity of rubber or other 75 impregnating material superposed thereon, the surplus being held back by such knife, which while not shown, is adjusted to the proper height by the screw-shafts I operated by the hand wheels I', which shafts are 80 attached to the knife at either end; K designates the upper or feed-roll mechanism carrying the roll F, of sheet-fabric H, about to be treated, from which roll the fabric H passes up over the knife-roll 11', just before it reaches the knife, being fed with a sufficient quantity of the rubber or other 85 treating material or fluid, usually delivered automatically from any suitable automatic feeding-receptacle, the surplus being held 90 back by the knife; and from the knife roll the top-ply of fabric H, passes over the drying bed C, usually of the steam-coil form shown, at the extreme end of which it passes downward over an idler-roll (not 95 shown), and the bottom-ply H', returns to the front, and is wound up on the take-up-roll L, all as clearly indicated in Fig. 2; the 100 length of the hot drying steam-coil bed being such that by the time the treated fab- 105

110

ric has passed over it to the end-roll (not shown), the rubber, etc., will have been thoroughly dried. The feed-roll K, and take-up-roll L, are of identical construction, 5 being at one period one, and then the other, and are each comprised of a rectangular roll-shaft, 20, upon which is mounted a roll-sleeve 21', usually for the sake of lightness of wood, having a square-central longitudinal bore to receive the shaft 20 so the shaft and sleeve will rotate in unison.

Axially mounted on, or connected with the shafts 20, at either end so as to rotate in unison therewith are wheels, which according to the varied positions of the shafts, in the feeding or take-up positions as hereinafter described, serve either as drive or brake-wheels, according to the exigencies of their particular position at the moment.

10 The roll shafts are supported in position upon the main-frame A' of the machine upon supporting-brackets 15 and 15' respectively, formed integral with the securing base-plate 14, secured by bolts 31 to the front end side-pieces or flanges 30' of the main-frame A'; which supporting-brackets are provided at their outer ends with suitable journal-boxes P in which such shafts 20 are revolvably supported. And in the 15 front forms of fabric-treating apparatus hitherto used, upon which my apparatus is an improvement, the wheels 28, 28' and 29, 29' are secured to the outer ends of the shafts 20, which extend through such journal-boxes P, which are provided on the upper sides or faces with slots (not shown), permitting of such shafts, wheels, etc., being lifted out of such journal-boxes. And hitherto in the operation of the machine this is 20 done by two men each taking hold of an end of the shaft and lifting the same clear, the lower take-up shaft L, carrying the finished roll of fabric F, (Fig. 3), after being taken out and placed upon a scale so as to 25 determine the increase in weight of the fabric, being then replaced in the upper and feed-roll journal-boxes of the brackets 15, while the empty feed-roll shaft of K, removed from such upper boxes is then 30 placed in position in the like journal-boxes of the lower-brackets 15', to act as a take-up or finish roll. And in this shift, by the machines and processes heretofore used, for 35 the reason that there may be some differences as to the thickness or quantity of the treating material fed to the two side edges of the fabric being treated, in order that such discrepancies of feeding may be overcome in order to make a smooth and perfect 40 coating or impregnation, etc., of the fabric (especially, when as in the higher grades of rubberized fabric), it is necessary to run the fabric a number of times through the machine, sometimes as many as five or six, 45 when the take-up roll is shifted into posi-

tion so as to become the feed-roll, it is also horizontally reversed, so that what was the right-side of such fabric-strip becomes when in the machine the left-side; and vice versa.

70 Thus it will be seen that in this shifting and weighing operation, the wheels, etc., add much to the weight to be shifted and two strong men are necessary to such shifting. In the carrying out of my improved 75 method herein disclosed, described, and claimed, by the form of apparatus for carrying the same into effect, also of my invention set forth herein, the brake and drive-wheels of the roll-shafts remain permanently in position in their journals, and only the center removable fabric-holding wooden slip-sleeves 21', and shafts 20, constituting the fabric-roll supporting portions of such shafts, are removed, thus 80 greatly lessening the weight necessary to be shifted; and by my improved combined roll-shifting and weighing apparatus, I obviate the necessity of removing the roll to be weighed from the vicinity of the machine 85 to a separate scale or weighing mechanism.

90 In my improved form of apparatus the combined drive and brake-wheels 28, 28', and 29, 29', instead of being secured upon the shafts 20 are secured in any desired 95 manner usually by means of cotter pins or set screws 22' upon short stud-shafts 17, 17', and 19, 19'. The wheels 28 and 29 being rigidly secured upon the outer ends of the stud-shafts 17 and 19, formed integral with 100 the stud-shaft socket-heads 22, having at their inner ends a square or rectangular orifice to receive the like shaped securing ends 22' of the roll-shafts 20, upon which are formed the cylindrical portions 23' for the 105 securing thereto (as hereinafter described), of the lifting releasable twin-hooks 52 secured to the ends of the two depending portions 51 and 51', comprising the lift-chains N. The stud-slip-shafts 17' and 19' are 110 each formed integral with a boss 27, against the outer face of which the pulleys 28' and 29' abut, which boss is provided with the journal inner portion or stud shaft sleeve P' which passes through the journal-box in 115 its particular bracket 15 or 15' and is provided at the end with the central axial slip-hollow 26', in which is slidingly held by means of the securing-pin 26 passing through the slot 25, the rear cylindrical 120 slip extension of the reciprocating stud-shaft socket head 23; a coil-spring 24 being interposed between the end of the main portion of the stud-shaft and the socket head 23, normally forcing such socket-head 125 23 out to the limit of the play of the securing-pin 26 in the slot 25, as clearly indicated in Fig. 3; and after insertion in place in the bracket-journal, the stud-shaft sleeve or journal inner portion P' is secured in 130

place by a collar 27', secured thereto by a set-screw, or in any other desired manner.

Secured above the brackets 15 and 15' usually and preferably parallel with the axes of rotation of the shafts 20, is an overhead trolley-rail 33 usually of the I-beam form shown, suitably supported in position, usually by being secured to the ceiling upon which travels the carriage-yoke 34, having the supporting traction-wheels 35, which yoke supports the main-bar 36 of the combined supporting trolley-carriage and weighing-scale D. Pivoted to a downward extension of the main-bar 35 by a pivot 36', is the vibrating scale-lever 37, the outer free end of which vibrates up and down between the two lock-cam supporting yoke-pieces 28 formed integral with the scale-lever 37, carrying at the lower end the lock-cam pivot-shaft 41', vibrated by the lock-cam lever 39', and carrying the lock-cam 39' shown in the vertical scale releasing and unlocking position, in Figs. 1 and 2.

Formed integral with or rigidly secured to the scale-lever 37 at its outer free end adjacent to the lock-cam 39, is the scale actuating-rod 40, connected with the scale-plunger or vertically reciprocating-shaft 41 by a pivot-bolt 42; the scale-mechanism 30 and dial being indicated by 43. Pivotedly supported by the scale-lever 37 adjacent to the center, is the supporting scale-hook 44, carrying the roll swing-lift supporting-chains 45 and 45', the outer ends of which 35 are hooked or otherwise firmly secured to the end journal-box pieces 46 and 46' of the lift swing-frame E, formed integral with the cross bar 47 and central journal-box piece 47', journaled in which is the drive-shaft 48, rotated through a sprocket-wheel 49, by an endless hand-chain 49', or by a power-pulley 50, driven by a belt. Also revolvably supported in lower journal-boxes formed in such pieces 46, 46', and 47', is the lift-chain shaft 55, upon the ends of which are secured the lift-chain gear-wheels 56 and 56', meshing with like smaller drive gear wheels 57, rigidly secured to the drive-shaft 48; and secured upon the ends of the 45 lift-chain shaft 44, are the lift-chain sprocket-wheels 54, actuating the roll supporting-chains N, provided at their ends 51 and 51', with the twin-hooks 52, for supporting the roll shaft 20 by being slipped over the cylindrical end portions 23' thereof.

Formed integral with the journal-box piece 46, of the lift-swing-shaft E is a bar 61 formed integral with a housing 60, through the center of which passes the drive-shaft 48, which housing contains within it a two-way reversible and releasable stop-pawl drive-shaft locking-device, and mechanism actuated and shifted by the shift-lever 62, whereby, by the throwing of such 65 lever 62 into the vertical position shown in

Figs. 1 and 2, the drive-shaft 48, and consequently the shaft 55 will be locked against rotation, and when shifted to the horizontal in one direction, will act as a stop-pawl against rotation in one direction, and when 70 in the opposite direction, reversibly, whereby as the chain 49' is operated such ratchet and pawl-mechanism will maintain the rolls being shifted at any desired height without danger of accidental displacement. 75

In carrying out my improved method herein disclosed, and operating my improved apparatus therefor, I take the following steps:

A roll of the fabric F yet untreated by 80 my improved process mounted upon the wooden axially rectangularly perforated-sleeve or mandrel 21', is slipped upon a rectangular feed-roll shaft 20, and the twin-hooks 52 of the ends 51' of the chain N 85 are thrown over the cylindrical lift portions 23', of said shaft and by manipulation of the drive chain 49', and the consequent rotation of the shafts 48 and 55, such fabric-roll and supporting-shaft are lifted 90 into the space between the feed-roll stud-shafts 17 and 17'; and the right hand rectangular end 22' of 20, being thrust into the like-shaped stud-shaft socket of the reciprocating stud-shaft-head 23, the shaft is 95 thrust back into the socket 26', against the tension of the spring 24, and the right hand end of such shaft 20 being brought into registry with the like socket of the stationary stud-shaft 22, it will be forced into the 100 same by the tension of the spring 24 and maintained in such position during rotation by the tension of such spring 24; or any suitable locking device (not shown) may be added to prevent accidental slipping of the 105 roll-shaft. When so placed in position, the end of the sheet of fabric forming the roll F is passed up from the under side of the roll, over the knife roll 11', and between the same and the knife (not shown), and 110 over the steam-coil drying-bed C, and after passing over the end roll (not shown) is threaded back underneath the drying-bed C and secured to a like wooden slip-sleeve 21', mounted in like manner upon the finish-roll or take-up-shaft 20, which has been placed in position in similar stud-shafts located in the journal-boxes of the lower outer journal brackets 15'. The manner of securing the end of the sheet to the take-up sleeve is immaterial and may be done by tacking, or any other desired manner; or even only by turning the take-up roll a number of times so as to wind several layers on the slip-sleeve 21'. The take-up finish-roll L 115 is rotated by either the wheel 28 or 28', usually by 28', usually by means of a belt O, (Fig. 1), driven from any suitable power-supply source. The feed-roll wheels 29 and 29' are provided with suitable adjustable brak- 120 125 130

- ing mechanisms Q, of any suitable form by which the fabric sheet is steadied and kept under tension in its passage through the machine.
- 5 The wheel 28' and take-up-shaft 20 and sleeve 21' being put into rotation to the right in the direction of the arrow in Fig. 2, the fabric is drawn off from the feed-roll and as it passes over the knife-roll 11', the fabric 10 at the knife-roll is supplied by hand or by an automatic-feeding-device, (not shown), with the required quantity of the impregnating or surfacing material to be deposited in or on such fabric, the surplus being removed 15 by the knife (not shown), located above such knife-roll hereinbefore referred to; and being thoroughly dried in its passage through the machine upon, over and along the steam-coil drying-bed C, is wound up on the take-up roll L; and before the last end is allowed 20 to pass over the knife-wheel, a threader lead-sheet of other material is attached to such end in the manner well known in the art, and such lead-sheet left in the machine to act 25 as a leader for the insertion of the same or another sheet, and when the front end of the lead-sheet is wound three or four times around the take-up-roll, the take-up-roll is reversed in rotation and the threader lead- 30 sheet separated from the treated fabric, thus preventing the labor and time that would be taken, in threading the fabric sheet by hand through the machine upon the continuation of the operation.
- 35 The combined weighing and lift-swing mechanism B carried by the trolley-carriage D, is then moved into position and the chains N having had their ends 51 secured to the empty-feed roll-shaft 20 at K by the placing 40 of the twin-hooks 52' upon the cylindrical portions 23' of such shaft, as clearly indicated in Fig. 1, while the filled take-up and finish-roll carrying the treated fabric-roll F, is secured in like manner to the ends 51', by. 45 the twin-hooks 52. The lock cam 39 is then by the movement of the lock-cam lever 39' to the horizontal-vertical and toward the right of Fig. 1, thrown into upward locking position so as to lock the scale-bar 37 against 50 downward movement, thus rendering the scale-mechanism inoperative, whereupon, by rotation of the drive-shaft 48, the lift-shaft 55 is (after the removal of the shafts 20 from their respective stud-shafts) rotated so 55 that the roll shafts are reversed as to vertical position; and also swung horizontally a half turn upon the pivot-hook 44, to bring about end for end reversal of the rolls, when they are again inserted in place in the stud- 60 shafts by which operation the rotation of the feed-roll K will be reversed; that is if the fabric sheet H has been first fed from the under-side of the feed-roll K, as indicated in Fig. 1; this reversal will cause it to be fed from 65 the top so as to bring what was the under and untreated side of the fabric-sheet uppermost, and in position to be itself treated, in the manner hereinbefore set forth. In some cases, and when only one side of the fabric is to be treated or coated, there is of necessity no such horizontal swinging of the rolls. 70 During this swinging operation the lock-chains 53 having the securing-hook 53' one of which is secured to the middle of the end- portions 51' of the lift chain N having been hooked into the end 51 of such on either side as indicated in dotted lines at 53" of Fig. 2, 75 which will prevent swinging apart of the rolls during the swinging reversal; while the rolls are, upon unhooking of such chains 80 maintained in any desired vertical position by proper manipulation of the pawl and ratchet shift-lever 62. While so suspended in position, (usually when the rolls are in quarter turn position) the lever 39', is thrown 85 down in to the vertical position shown in Figs. 1 and 2, so as to unlock the scale-lever 37, when the weight of the finish-roll, 90 of the two-rolls and the fabric, and the swing shift-mechanism will be indicated upon the scale-dial 43; and the tare of the supporting mechanism, and the weight of the fabric and its square-yardage surface being known, this weighing between each passage through the machine, by a simple mathematical computation, will at once determine, when the required grade of treated fabric has been reached, whereupon the finished-roll of fabric F is removed, and 95 a new and untreated roll inserted for like treatment.
- It is evident that many changes and modifications in my improved method of fabric treatment, and also in the construction, arrangement and combination of the several 100 elements of my improved apparatus for carrying the same into effect, herein disclosed, may be made without departing from the scope of my invention, and I do not intend to limit myself to the exact construction of 105 apparatus, nor to all steps, nor to the exact sequence of steps herein disclosed, shown and described.
- I claim:
1. In a device of the class described, the combination with a fabric impregnating, loading, or coating machine, in the passage through which the sheet or strip of fabric to be treated is taken from a feed-roll, passed through the machine, and is taken up upon a take-up or finish-roll; of means for removably revolubly supporting the feed and finish-rolls adjacent to one another at the feed-end of the treating-machine; a combined feed and finish-roll shifting and 120 weighing-device adapted to be brought into and out of connection with such feed and finish-rolls, by which such feed and finish-rolls may be removed from and re-inserted in the treating-machine and the increase in 125
  2. In a device of the class described, the combination with a fabric impregnating, loading, or coating machine, in the passage through which the sheet or strip of fabric to be treated is taken from a feed-roll, passed through the machine, and is taken up upon a take-up or finish-roll; of means for removably revolubly supporting the feed and finish-rolls adjacent to one another at the feed-end of the treating-machine; a combined feed and finish-roll shifting and 130 weighing-device adapted to be brought into and out of connection with such feed and finish-rolls, by which such feed and finish-rolls may be removed from and re-inserted in the treating-machine and the increase in

weight of the fabric being treated on each passage through the machine may be determined by the difference in weight indicated on the weighing scale during the process of 5 the roll shifting.

2. In a device of the class described, the combination with a fabric impregnating, loading, or coating machine, in the passage through which the sheet or strip of fabric 10 to be treated is taken from a feed-roll, passed through the machine, and is taken up upon a take-up or finish-roll; of means for removably revolubly supporting the feed and finish-rolls adjacent to one another at the feed- 15 end of the treating-machine; a combined feed and finish-roll shifting and weighing device adapted to be brought into and out of connection with such feed and finish-rolls, by which such feed and finish-rolls may be 20 removed from and re-inserted in the treating-machine in reversed position and the increase in weight of the fabric being treated on each passage through the machine may be determined by the difference in weight 25 indicated on the weighing scale during the process of the roll shifting and reversal.

3. In a device of the class described, the combination with a fabric impregnating, loading, or coating machine, in the passage 30 through which the sheet or strip of fabric to be treated is taken from a feed-roll, passed through the machine, and is taken up upon a finish-roll; of two oppositely disposed axially coincident revoluble feed-roll stud- 35 shafts supported at the front or feed-end of the machine; two like take-up or finish-roll stud-shafts supported in like manner adjacent to and axially parallel with the feed-roll stud-shafts; two removable roll- 40 shafts adapted to be inter-changeably connected with either set of stud-shafts so as to serve either as the feed-roll or take-up or finish-roll-shaft according to position; a reversible lift-chain apparatus having chains 45 adapted to be adjustably secured at coincident ends to one of the removable supporting rolls, and at the other end to the like-ends of the other supporting roll; a lift-carriage; a sprocket-wheel shaft carried by the lift-carriage; 50 the lift-carriage; sprocket-wheels for actuating each of said chains mounted upon the sprocket-wheel-shaft; and mechanism for actuating such sprocket-wheel shaft so as to vertically reversely shift the two removable roll-shafts.

4. In a device of the class described, the combination with a fabric impregnating, loading, or coating machine, in the passage through which the sheet or strip of fabric 60 to be treated is taken from a feed-roll, passed through the machine, and is taken up upon a finish-roll; of two oppositely disposed axially coincident revoluble feed-roll stud- 65 shafts supported at the front or feed-end of the machine; two like take-up or finish-roll

stud-shafts supported in like manner adjacent to and axially parallel with the feed-roll stud-shafts; two removable roll-shafts adapted to be inter-changeably connected with either set of stud-shafts so as to serve 70 either as the feed-roll or take-up or finish-roll-shaft according to position; a reversible lift-chain apparatus having chains adapted to be adjustably secured at coincident ends to one of the removable supporting rolls, 75 and at the other end to the like-ends of the other supporting roll; a lift-carriage; a sprocket-wheel shaft carried by the lift-carriage; sprocket-wheels for actuating each of said chains mounted upon the sprocket-wheel-shaft; mechanism for actuating such sprocket-wheel shaft so as to vertically reversely shift two removable roll-shafts; and a weighing-scale apparatus supporting the lift-carriage. 80

5. In a device of the class described, the combination with a fabric impregnating, loading, or coating machine, in the passage through which the sheet or strip of fabric to be treated is taken from a feed-roll, passed through the machine, and is taken up upon a finish-roll; of two oppositely disposed axially coincident revoluble feed-roll stud- 90 shafts supported at the front or feed-end of the machine; two like take-up or finish-roll stud-shafts supported in like manner adjacent to and axially parallel with the feed-roll stud-shafts; two removable roll-shafts adapted to be inter-changeably connected with either set of stud-shafts so as to serve 95 either as the feed-roll or take-up or finish-roll-shaft according to position; a reversible lift-chain apparatus having chains adapted to be adjustably secured at coincident ends to one of the removable supporting rolls, and at the other end to the like-ends of the other supporting roll; a lift-carriage; a sprocket-wheel shaft carried by the lift-carriage; sprocket-wheels for actuating each of said chains mounted upon the sprocket-wheel-shaft; mechanism for actuating such sprocket-wheel shaft so as to vertically reversely shift the two removable roll-shafts; and a weighing-scale apparatus supporting the lift-carriage, the lift-carriage being 100 connected with the weighing-scale apparatus by a vertical pivot-support, upon which the lift-carriage may be horizontally revolved or vibrated. 110

6. In a device of the class described, the combination with a fabric impregnating, loading, or coating machine, in the passage through which the sheet or strip of fabric to be treated is taken from a feed-roll, passed through the machine, and is taken up upon a finish-roll; of two oppositely disposed axially coincident revoluble feed-roll stud- 120 shafts supported at the front or feed-end of the machine; two like take-up or finish-roll stud-shafts supported in like manner ad- 125

adjacent to and axially parallel with the feed-roll stud-shafts; two removable roll-shafts adapted to be inter-changeably connected with either set of stud-shafts so as to serve either as the feed-roll or take-up or finish-roll-shaft according to position; a reversible lift-chain apparatus having chains adapted to be adjustably secured at coincident ends to one of the removable supporting rolls, and at the other end to the like-ends of the other supporting roll; a lift-carriage; a sprocket-wheel shaft carried by the lift-carriage; sprocket-wheels for actuating each of said chains mounted upon the sprocket-wheel-shaft; mechanism for actuating such

sprocket-wheel shaft so as to vertically reversely shift the two removable roll-shafts; and a weighing-scale apparatus supporting the lift-carriage, the lift-carriage being connected with the weighing-scale apparatus by a vertical pivot-support, upon which the lift-carriage may be horizontally revolved or vibrated, and the weighing-scale apparatus being provided with means for rendering the same operative or inoperative as desired.
